COMBINED GAME TABLE AND SEATING UNIT

Caine Turner, 938 W. 46th St. 90037, and Connie Marie Turner, 1926 W. 66th St. 90047, both of Los Angeles, Calif.

Filed May 7, 1973, Ser. No. 357,550

Term of patent 14 years

Int. Cl. D6—03

U.S. Cl. D6—45

FIG. 1 is a side elevation of a combined game table and seating unit showing our new design;

FIG. 2 is a plan view thereof; and

FIG. 3 is an end view thereof.

The side of the article not shown is a mirror image of the side shown in FIG. 1.

We claim:

The ornamental design for a combined game table and seating unit, as shown and described.
